ATTORNEY

UNITED STATES PATENT OFFICE.

FRANK. AURNHAMMER, OF HOLYOKE, MASSACHUSETTS.

HYDROGEN-LAMP.

SPECIFICATION forming part of Letters Patent No. 432,590, dated July 22, 1890.

Application filed February 9, 1889. Serial No. 299,244. (No model.)

To all whom it may concern:

Be it known that I, FRANK. AURNHAMMER, a citizen of the United States, residing in Holyoke, in the county of Hampden and State 5 of Massachusetts, have invented new and useful Improvements in Hydrogen-Lamps, of which the following is a specification, reference being had to the accompanying drawings and letters of reference marked thereon, 10 in which—

Figure 1 is an elevation in section on line *x x*. Fig. 2 is a like view taken on line *t t*, and Fig. 3 is a top or plan view of the device.

Like letters of reference indicate like 15 parts.

The construction and operation are as follows: A jar is provided in which is deposited dilute sulphuric or other acid for the production of gas. To the top of the jar is secured 20 a plate or cover *b*, which may be cemented or otherwise tightly secured in position. A cap *c* is secured to the plate *b*, preferably by being threaded and screwed therein, as shown. The cap *c* is provided with a part *d*, within 25 which a valve or cock is properly arranged. The plug *e* is provided with a collar *g*. An opening is provided in the cap, which extends downward from the location of the collar *g* and opens into the jar. A lifting-rod *h* is 30 connected at one end with the collar *g* and at its opposite end with a pivotal lever *i*, pivoted at the point *y*. A rod *j* extends from the pivotal lever *i* to a block *k*, which block is of zinc or other material adapted to produce the 35 desired results when immersed in the acid, the block being suspended or supported by the rod *j*. The lever *i* is provided with an arm *m*, upon which is mounted a coiled spring *l*, which serves to maintain the lever *i* and 40 parts attached thereto in their normal position, as shown in the drawings. The plug *e* is made tapering from the nozzle end downward, and is tightly fitted within the part *d*, and is provided with levers or arms *f*. The 45 plug is also provided with an interior opening tapering toward the nozzle end, and is provided with an opening *s*, arranged to register with the opening *r* in the cap when the plug is turned to the desired position. To the plate 50 or cover *b* is secured a standard *n*, provided with a ring *n'*, into which ring is fitted a thimble or cylindrical piece *o*, and within the part *o* is arranged a platina sponge *p*. The

platina sponge and its support are of course arranged opposite the nozzle-opening of the 55 plug *e*.

When the device is not in use, the operative parts remain in the position shown in the drawings. The block *k* is not, therefore, in contact with the acid, and no chemical action 60 takes place, and therefore no loss results. When, however, it is desired to set the device in operation, the levers or arms *f* are revolved or moved a short distance, this causing the plug *e* to be turned, bringing the opening *s* 65 in register with the opening *r*, lowering the rod *h*, turning the lever *i* upon its pivot, lowering the rod *j*, and lowering the block *k*, thus bringing the block in contact with the acid, when chemical action immediately results 70 and hydrogen gas is evolved, which escapes through the openings *r* and *s*, and thence through the nozzle-opening of the plug *e* in a fine jet, impinging against the platina sponge *p*, which produces a flame. Immediately upon 75 a release of the levers *f* the spring *l* operates to return the parts to their normal position and the production of the gas ceases.

Having therefore described my invention, what I claim, and desire to secure by Letters 80 Patent, is—

1. In an apparatus of the kind shown, the combination of a jar and cover fitting the same, the upper portion of the cover being projected upward and provided with a rotatable plug *e*, provided with openings, as stated, and a hand-wheel *f*, mounted on said plug, a lever *i*, pivoted between its ends to a bar on the inner face of the cover, and provided with a spring *m*, mounted upon an arm projecting 85 from the lever *i*, a rod *h*, attached at one end to the lever *i* and at the opposite end to the plug *e*, and a rod *j*, attached to the lever *i* opposite the point of connection of rod *h* therewith, substantially as shown. 95

2. The combination of a jar *a*, cover *b*, cap *c*, provided with a part *d*, a plug *e*, provided with openings and having levers *f* attached, collar *g*, mounted on the plug, rod *h*, lever *i*, having arm *m*, with spring *l* mounted thereon, rod *j*, and block *k*, substantially as and for the purpose shown. 100

FRANK. AURNHAMMER.
